US0D1006766S

(12) **United States Design Patent** (10) Patent No.: **US D1,006,766 S**
(45) Date of Patent: ** Dec. 5, 2023

(54) **ACTUATOR**

(71) Applicant: **Olsbergs Electronics AB**, Vallentuna (SE)

(72) Inventors: **Christopher Hokander**, Vallentuna (SE); **Jan-Erik Steen**, Vallentuna (SE)

(**) Term: **15 Years**

(21) Appl. No.: **35/515,102**

(22) Filed: **Jul. 21, 2022**

(80) **Hague Agreement Data**

Int. Filing Date: **Jul. 21, 2022**

Int. Reg. No.: **DM/223042**

Int. Reg. Date: **Jul. 21, 2022**

Int. Reg. Pub. Date: **Sep. 9, 2022**

(51) **LOC (14) Cl.** **14-03**

(52) **U.S. Cl.**

USPC **D13/168**; D34/35; D15/142

(58) **Field of Classification Search**

USPC D13/164, 168; D14/218, 401; D15/138, D15/199; D34/34, 35

CPC H03J 1/0025; H01H 9/0235; H04B 1/202; B66C 13/04; B66C 13/18; B66C 13/40; B66C 2700/088

See application file for complete search history.

(57) **CLAIM**

The ornamental design for an actuator, as shown and described.

DESCRIPTION

1.1 is a left front perspective view of a first embodiment of the actuator.

1.2 is a right rear perspective view.

1.3 is a front view.

1.4 is a rear view.

1.5 is a left view.

1.6 is a right view.

1.7 is a top plan view.

1.8 is a bottom view.

2.1 is a left front perspective view of a second embodiment of the actuator.

2.2 is a right rear perspective view.

2.3 is a front view.

2.4 is a rear view.

2.5 is a left view.

2.6 is a right view.

2.7 is a top plan view.

2.8 is a bottom view.

1 Claim, 16 Drawing Sheets
